C. C. HANSEN,
CASING CUTTING TOOL,
APPLICATION FILED JUNE 22, 1921.

1,406,853.

Patented Feb. 14, 1922.

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

CASING-CUTTING TOOL.

1,406,853.

Specification of Letters Patent. Patented Feb. 14, 1922.

Application filed June 22, 1921. Serial No. 479,535.

To all whom it may concern:

Be it known that I, CHARLES C. HANSEN, a citizen of the United States, and a resident of Easton, county of Northampton, State 5 of Pennsylvania, have invented a certain Casing-Cutting Tool, of which the following is a specification accompanied by drawings.

This invention relates to boring drills and more particularly to apparatus forming a 10 part of such drills for cutting or separating the casing while in the well so that the upper part of the casing may be cut off and removed or else the lower collapsed part of the casing may be disintegrated by blasting 15 or cut out by a calyx tool.

In the drilling of wells a cylindrical casing is sunk forming a lining in which the drill bit operates. Such wells are often sunk to considerable depths so that if a portion 20 of the casing collapses, the removal of the casing or lining or any part of it presents peculiar difficulties.

The object of the present invention is to enable the upper portion or portions of a 25 cylindrical well casing or lining if desired to be easily and quickly removed from the hole if the casing sticks or becomes jammed, by cutting the casing at any desired point or points above the jammed portion, the cut 30 sections being readily raised to the surface of the ground in any desired manner, and also to permit the disintegration of the lower portion.

A further object is to accomplish the 35 above cutting operation by means of a simple compact apparatus forming a part of the drill and operated and controlled by the same means which operate the drill.

Further objects of the invention will 40 hereinafter appear and to the ends set forth, the invention consists of the features of construction and combinations of parts described and claimed in the following specifications and shown on the accompanying 45 drawings, forming a part hereof, which illustrates one preferred practical embodiment of the invention, in which—

Figure 1 is a longitudinal view partly in section of a drill bit embodying the casing 50 cutter, as the parts appear prior to insertion of the bit within the casing;

Figure 2 is a longitudinal sectional view on the line 2—2 of Figure 4 and at right angles to that shown in Figure 1, showing

the apparatus in operation within a well 55 casing;

Figure 3 is a transverse sectional view taken on the line 3—3 of Figure 1, showing the cutters in retracted position;

Figure 4 is a transverse sectional view 60 on the line 4—4 of Figure 2, showing the cutters in operative cutting position;

Figure 5 is a perspective view of the cam or wedge member, for operating the cutters, and

Figure 6 is a similar view of the jar block 65 for imparting blows of impact to the cam or wedge member.

In the drawings a cylindrical well casing A is shown forming a lining for a drilled 70 hole. The casing cutting apparatus consists of the usual hollow cylindrical barrel B having a drive head C threaded into and enclosing the upper end and a guide plug D threaded into and closing the lower end. A 75 hollow drill rod E of usual form is screwed into the drive head C and this drill rod E is adapted to be rotated by any suitable and usual means commonly employed to rotate a well drilling tool to effect rotation of the 80 barrel B. The apparatus may be adapted to feed water through the drill to facilitate the boring but as this feature forms no part of the present invention it will not be described in detail.

A cylindrical hollow two part plug F is secured within the lower part of the barrel B by screws G or any other desired means. This two part plug F has a longitudinal 85 passage or opening H preferably of rectangular cross-section and a transverse opening J is formed approximately centrally thereof. In the opening J a pair of oppositely disposed cutters K and L are mounted, which are normally withdrawn 90 within the periphery of the barrel B but in operation are adapted to be moved outwardly so that the cutting edges M and O respectively extend through apertures P and Q in the wall of the barrel B and engage 95 the wall of the well casing A which is desired to be cut. Rotation of the barrel B in the direction shown by the arrows, Figure 4, causes the cutting edges M and O to make a circular cut P' through the wall of 100 the casing A.

The cutters are pushed into extended position to forcibly engage the wall of the casing

A by means of a longitudinal cam or wedge member R which acts to force the cutters apart by a wedging action. This member R is generally angular in section to fit the 5 passage H in the plug F and the lower end portion S is adapted to slide in the said passage H so that the member R rotates with the barrel B. The said portion S of the member R is formed with oppositely inclined 10 longitudinal cams or wedges T and U and the cutters K and L have portions of their contiguous sides cut away forming recesses V and W with which the inclined edges of the wedge member portions T and U respectively are adapted to engage. The ends 15 X of the wedge portions T and U may be reduced in width for a short distance, so that the wedge portions may withdraw the cutters and lie within the recesses V and W 20 when the wedge member is raised without forcing the cutters K and L outwardly and the length of the wedge member R is such that the upper end or head Y may be drawn up against the lower surface of the drill 25 head C and held there when the cutters are not in use.

Above the wedge portions T and U the member R is provided with shouldered lugs Z and a reduced stem a of any desired 30 length connects the body of the member with the head Y. A cylindrical jar block b is adapted to slide on the stem a within the limits allowed by the lugs Z and head Y, the jar block b being recessed and open at 35 one side to enable it to be placed over the stem a. One end of a length of wire or any other rope e is secured at f to the upper end of the jar block b and passes through a longitudinal passage g in the drill head C. 40 The opposite end of the rope is secured by means of a suitable clamp h to the drill rod E at any desired point and may be tied to hold the wedge member in uppermost inoperative position as shown in Figure 1. 45 It is to be understood, that the drill rod and the rope may be of any desired length, according to the depth of the hole, the essential feature being that a portion of the rope is accessible to the drill operator for 50 pulling up and dropping the jar block upon the wedge member to impart blows of impact, when the rope is loosened.

In the operation of the apparatus, when 55 it is desired to cut off a section of well casing, the barrel B is adjusted within the well casing to the depth desired and rotative movement imparted to the barrel in the usual manner as in drilling. The rope e is loosened so that the wedge member and 60 jar block are lowered to the position indicated in Figure 2. As the barrel rotates the operator repeatedly grasps the rope e and pulls on the same and then lets go so that the jar block falls on the shouldered 65 lugs Z, hammering the wedge member and

forcing it downwardly. The oppositely inclined portions T and U of the wedge member engage the cutters as the wedge member is driven downwardly, and the cutters are forced outwardly, engaging the inner wall 70 of the well casing and cutting a circular groove of increasing depth until the desired portion of the casing is completely severed from the remainder. The wedge member R serves to maintain the cutter tightly 75 against the well casing during the cutting. When it is desired to withdraw the cutters the rope e is pulled upward and the wedge member R is thus retracted to its normal position, the head Y engaging the lower surface of the drill head C and the cutters, following the inclined portions T and U, are restored to their normal position in the transverse bore J within the circumferential 80 limits of the barrel. When the casing has been cut the severed portion is readily removed in any desired manner.

This form of casing cutter has been found efficient in use, is simple in construction and cheap to manufacture. While the specific form shown has been found to be a preferred form of device for carrying out the objects of the invention, other forms may occur to those skilled in the art and scope of the invention as defined in the appended claims; hence it is not desired to limit the invention to the form herein specifically shown and described.

I claim:

1. A casing cutting tool comprising a 100 barrel adapted to be rotated in a well casing, oppositely disposed cutters mounted transversely in said barrel and normally held within the circumferential limits thereof, a wedge member engaging said cutters and a jar block adapted to intermittently forcibly engage said wedge member forcing the cutters outwardly whereby said cutters engage the well casing and cut a circular 105 groove of increasing depth therein as the barrel rotates, separating a portion of the casing from the remainder.

2. A casing cutting tool comprising a barrel adapted to be rotated in a well casing, oppositely disposed cutters mounted transversely in said barrel and normally held within the circumferential limits thereof, a wedge member having oppositely inclined 110 portions engaging said cutters for moving said cutters outwardly to engage the wall of the casing, a jar block slidable on said wedge member, and manual means for raising and lowering said jar block whereby the jar block forcibly engages the wedge member and the cutters are forced outwardly 115 cutting a circular groove of increasing depth in the well casing as the barrel rotates and severing a portion of the casing from the remainder.

3. A casing cutting tool comprising a 120

barrel adapted to be rotated in a well casing, oppositely disposed cutters mounted transversely in said barrel and normally held within the circumferential limits thereof, a wedge member engaging said cutters, a jar block slideable on said wedge member and manual means for raising and lowering said jar block for intermittently jarring said wedge member, to force the cutters outwardly as the barrel rotates, said manual means being also adapted to withdraw the jar block and wedge member to restore the cutters to normal inoperative position.

In testimony whereof I have signed this specification.

CHARLES C. HANSEN.
